[57] **CLAIM**

The ornamental design for safety stirrup, as shown and described.

DESCRIPTION

FIG. 1 is an environmental perspective view of a safety stirrup showing my new design;
 FIG. 2 is a top plan view thereof;
 FIG. 3 is a bottom plan view thereof;
 FIG. 4 is a front elevational view thereof;
 FIG. 5 is a right side elevational view with the left side being a mirror image thereof; and,
 FIG. 6 is a rear elevational view thereof.

The broken line showing of a portion of a tack in FIG. 1 is for illustrative purposes only and forms no part of the claimed design.
